CLAIM

The ornamental design for an electrical outlet protector, as shown and described.

DESCRIPTION

FIG. 1 is a front and upper right perspective view of an electrical outlet protector showing my new design. The broken line showing is included for the purpose of illustrating environmental elements only and forms no part of the claimed design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof;

FIG. 7 is a bottom view thereof; and,

FIG. 8 is an exploded front perspective view thereof.

FIG. 1

FIG. 2

FIG. 3

FIG. 4

FIG. 5

FIG. 6

FIG. 7
